UNITED STATES PATENT OFFICE.

GEORGE LEWIS HOGAN, OF NEW YORK, N. Y., ASSIGNOR, BY DIRECT AND MESNE ASSIGNMENTS, OF ONE-FOURTH TO WILLIAM ERNEST HOLLAND, OF CHICAGO, ILLINOIS, AND THREE-FOURTHS TO AERO MANUFACTURING COMPANY, OF CHICAGO, ILLINOIS, A CORPORATION OF ILLINOIS.

VAPOR-BURNING APPARATUS.

1,104,732.

Specification of Letters Patent.

Patented July 21, 1914.

Application filed January 25, 1913. Serial No. 744,205.

To all whom it may concern:

Be it known that I, GEORGE LEWIS HOGAN, of the city of New York, N. Y., United States of America, and temporarily residing at 56 5 Sherbrooke street west, Montreal, Province of Quebec, Canada, have invented certain new and useful Improvements in Vapor-Burning Apparatus; and I do hereby declare that the following is a full, clear, and 10 exact description of the same.

My invention relates to apparatus such as lamps or stoves in which volatile fuel is used for the production of light, heat or power and wherein air is first mixed with 15 the fuel and the mixture then conveyed to the ignition point, the proportion of such mixture being regulated and the travel of the same controlled by intermediate devices to which this invention has particular reference. 20

An object of the present invention is to provide a vapor burning apparatus which is of a simple and inexpensive construction, one advantage being the unimpeded interior 25 passages which present a practically straight travel for the vapor, etc., thus reducing the resistance offered to the latter and increasing the efficiency of the apparatus for the reason that minimum suction is necessary in its 30 operation.

A further object is to improve the general construction of this type of apparatus by first—providing a simple device for regulating, in an easy and effective manner, the 35 mixture of the fuel and air, second—protecting the interior vapor passages from the effect of disturbances of the air at the exterior of the apparatus, and third—providing a device which compensates for and 40 overcomes the disadvantages resulting from the difference in condition of the fuel mixture at different times in the course of the operation of the apparatus.

For full comprehension, however, of my 45 invention reference must be had to the accompanying drawings forming a part of this specification in which similar reference

characters indicate the same parts and wherein;

Figure 1 is a vertical section of a vapor 50 burning lamp constructed according to my invention; Fig. 2 is a side elevation of the lamp in use and supported upon a stand; Fig. 3 is a horizontal section on line 3—3 Fig. 1; Fig. 4 is a perspective view of the 55 compensating device; Figs. 5 and 6 are horizontal sections on lines 5—5 and 6—6 respectively, Fig. 1; and Fig. 7 is a detail section of a modified form of my invention.

By way of example I have illustrated a 60 vapor burning lamp in the drawings and will now describe my invention with reference to the same.

The lamp is of the type embodying a carburetor consisting preferably of a drum or 65 casing *b* inclosing a liquid fuel absorbing block or equivalent *c* held in place by lugs *d* upon the interior of the casing and having air passages *e* therethrough. The end walls *f* of the casing present chambers *g* and *h*, 70 respectively, the chamber *g* or air chamber has an opening through the top thereof within which is screwed a fitting *i* presenting one or more air vents *j*.

The burner of the lamp consists of a 75 flared base *k* resting loosely upon a spinning *l* soldered or otherwise secured to the fitting *i* and overhanging the top of the casing *b*. Extending from the base *k* is a tube or hollow standard *m* having the gallery *n* supported thereby near the top with the chimney *o* and mantle *o'*. 80

The base *k* of the burner is provided with inlets *p* through which the air enters and passes through the vents *j*, to the air chamber *g* and from where it is distributed, by a plate *q*, to the passages *d* in the absorbent block, and so passes to the chamber *h*. As the air passes through the passage *d* it becomes charged with the liquid fuel and collects in the lower chamber *h* in the form of vapor which is conveyed to the burner through a tube *r* located within a passage *s*. This passage is preferably formed in the 90

- block *c* and in line with the fitting *i*. The tube *r* extends from the passage *s* and passes loosely through the fitting *i* to a point within the hollow standard *m*.
- 5 In order to mix air with the vapor in the tube *r* I have formed one or more vents or slots *t* near the bottom of the latter and as a portion of the air from the chamber *g* passes down through the passage *s* it will 10 enter these vents and mix with the vapor. To control the quantity of air entering the tube and therefore regulate the proportion of the mixture in the tube *r* I have arranged the latter so that it is free to be moved longitudinally and in this way when a small 15 amount of air is required the tube is moved to bring the vents away from the top or air inlet end of the passage and when a greater quantity of air is required the tube is moved 20 up and the vents therein brought nearer to the top of the passage. This regulation of the air to the tube *r* is made more effective by reducing the lower end of the passage *s* to closely inclose the tube so that when the 25 latter is lowered the vents *t* are closely adjacent to the sides of the passage and the approach of air thereto further obstructed. To obtain this effect the passage may be tapered but I prefer to form it as shown in the drawings 30 wherein I have formed a shoulder *u* at a point about midway of the passage and at such a height, relatively to the tube when in its lower position, that the top of the reduced portion is about level with the tops of 35 the vents *t* in the tube. To prevent crumpling of the absorbent block I have provided a bushing *v* in the passage *s* which is preferably held in position by a lateral flange *w* extending into the block.
- 40 The tube *r* is longitudinally moved by a handle 2 which is secured to the tube and extends upwardly at the side of the latter, loosely through the fitting *i* and through the base *k* of the burner where it is preferably bent to form a hand piece. The tube 45 is yieldingly held in any adjusted position by a spring detent 4 carried by the fitting *i* and passed through the latter to engage with the tube while, in like manner, the position of the handle 2 is yieldingly maintained by a 50 spring 5.
- Between the bottom of the fitting *i* and the top of the passage *s* is loosely located a washer 6 through which the tube *r* and the handle 2 passes, while upon the tube, at a 55 desired point near the lower end thereof, are oppositely located pins or projections 7 which at a certain point in the upward travel of the tube, engage with the washer 6 and cause the latter to close the air vents *j* and so stop the operation of the lamp.
- Secured within the base *k* of the burner and at a point between the air inlets *p* and the air vents *j* in the fitting *i*, is a horizon-

tally disposed perforated plate 8 which acts 65 as a baffle plate and protects the interior of the lamp from disturbances due to high winds, etc., outside the lamp and in this way a steady current of air is directed through the vents *j* and fluctuations in the flame obviated. 70

When the lamp is first lighted the absorbent block will give off an abundance of fuel and the vapor in the chamber *h* will accordingly be very rich and require to be 75 mixed with a considerable quantity of air whereas later on, as the fuel supply becomes depleted, the vapor will not be so rich and need only a small amount of air. To compensate for this difference in condition of 80 the vapor I have provided a device which is located in the vapor chamber and consists of a disk 9 or sheet of soft wood or other absorbent material such as fiber, which is suspended below the block *c* by a strip 10 of 85 springy metal secured at one end to the wall of the chamber and having the disk fastened to its opposite end. When the block *c* is being charged with fuel the disk 9 will also become saturated and expand out of its normal state to a position closer to the block *c* 90 as seen in dotted lines Fig. 1, and partially obstruct the passages *e*, so that when the lamp is first lighted the flow of vapor from such passages will be reduced but the operation of the lamp is not interfered with because only a partial supply of the rich vapor 95 is necessary and as upon raising the tube *r* to allow the air to enter the same a mixture in proper proportion and quantity is conveyed to the burner. As the fuel in the block *c* becomes depleted it will be proportionately exhausted from the disk 9 permitting the latter to assume its normal position and not obstruct the passages *d* and in this 100 way a fuller supply of a weaker vapor is carried to the tube *r* and the latter lowered to restrict the air supply thereto as may be desired.

The burner is of the usual construction 110 with the exception of a chamber 11, having air vents 12, formed below the gallery *n*, around the outside of the standard *m* and communicating with the chimney. The chamber 11 is provided with an aperture 14 115 through which a lighted match or other flame may be inserted, the flame rising at the side of the mantle and causing a suction which draws the vapor up through the standard *m* and ignites the same. A minimum amount of suction is required which is due to the straight and practically unimpeded passages provided for the air and vapor by my improved construction. In order 120 to close the aperture 14 I have provided a member 15 in the chamber which is adapted to slide over such aperture, the member 125 preferably comprising an inner ring slid-

ably located with relation to the wall of the chamber, slotted with an aperture 16 to register with the aperture 14 and adapted to be moved to close the latter by a lug 17 extending through a circumferential slot 18 in the wall of the chamber.

As is usual in lamps of this type the burner is removable and in this instance the burner is, as above mentioned, resting 10 loosely upon the spinning *l* and held in position by the baffle plate 8 which encircles the tube *r*. The base *k* of the burner is radially slotted as at 20 and the baffle plate 8 is correspondingly slotted to accommodate 15 the handle 2 and avoid interference with the latter when the burner is removed.

The handle 2 may be of wire but in my preferred construction it is formed of small bore pipe and engages the tube *r* at a point 20 just above the vents *t*, that is to say at a point below the normal level assumed by the vapor in the tube which is substantially above the horizontal center of the block *c*. One end of the handle is loosely passed 25 through the tube *r* and turned up as at 22 and has a bulb 25 attached at its opposite end and by pressing the bulb a forced draft can be produced in the tube *r* which, commencing below the level of the 30 vapor, positively forces the same up into the burner.

In Fig. 7 I have shown a modification wherein my invention is applied to a stove, the pipe 24 leading to the burner of the latter. The operation of the stove is the same as the lamp with the exception that the tube *r* is below the fitting *i* and the top of such tube engages the washer 6 to close the inlet in the fitting while the handle 2 40 extends up through the fitting and is yieldingly supported by the spring 5 and in turn supports the tube.

What I claim is as follows:

1. A liquid fuel burning apparatus including a burner and a carbureter having an air chamber, a vapor chamber, an absorbent medium between the two chambers, an unobstructed passage leading from one end of the absorbent medium to the other 45 and a longitudinally movable tube within the said passage and in operative relation with the burner, said tube being of a size to form an uninterrupted space between its exterior surface and the interior surface of 50 the passage and for the full length of said passage.

2. In a vapor burning lamp, the combination with a burner, of a carbureter including an absorbent block having a passage therethrough, an air chamber at the top of the block, a vapor chamber at the bottom of the block, a longitudinally movable tube in the passage, extending to the burner and having vents therein near the bottom, means

for vertically adjusting the tube and a spring 65 for retaining the tube in its adjusted position.

3. In a vapor burning lamp, the combination with a burner, of a carbureter including an absorbent block having a passage therethrough, an air chamber at the top of the block, a vapor chamber at the bottom of the block, a longitudinally movable tube within the passage, extending to the burner and having vents therein near the bottom and a 70 pipe extending from the exterior of the lamp 75 through said passage to the interior of the tube.

4. In a vapor burning lamp, the combination with a burner, of a carbureter including 80 an absorbent block, an air chamber at the top of the block, a vapor chamber at the bottom of the block, a fitting extending through the top chamber and presenting air vents therethrough, a washer located between 85 the bottom of the said fitting and the top of the block, a longitudinally movable tube extending through the block and presenting a projection adapted, at a predetermined point in the movement of the tube, to engage with 90 the washer and carry the same against the fitting to cover the vents in the latter.

5. A vapor burning apparatus including a carbureter having an absorbent block with a passage therethrough, an air chamber at 95 the top of the block, a longitudinally movable tube located in said passage, a handle attached to the tube and extending therefrom to the exterior of the apparatus and a spring yieldingly holding the tube in position. 100

6. A vapor burning apparatus including a carbureter having an absorbent block with a passage therethrough, an air chamber at the top of the block, a longitudinally movable tube located in said passage, a cover for the carbureter and having a slot therein, a handle attached to the tube and extending therefrom through the air chamber and through the slot in the cover to the exterior 110 of the apparatus and spring bearing against the tube and the handle for yieldingly holding them in position.

7. In a vapor burning lamp including a burner, a base and a carbureter, an air passage leading from the base of the burner to the carbureter, air inlets in the base of the burner, an air distributing plate adjacent to the carbureter and a perforated baffle plate between the said air inlets and the air passage to the carbureter. 115 120

8. In a liquid fuel burning apparatus, a carbureter including an air chamber, a vapor chamber, an absorbent block between the two chambers and having a passage 125 therethrough with one end reduced in size, a bushing within the passage at the reduced end thereof, a lateral flange upon the bush-

ing and embedded in the absorbent block and a tube in the said passage and having vents therein.

9. In a vapor burning lamp, the combination with a burner, of a carbureter including an absorbent block having a passage therethrough, an air chamber at the top of the block, a vapor chamber at the bottom of the block, a longitudinally movable tube 10 within the passage, extending to the burner and having vents therein near the bottom, a

pipe extending from the exterior of the lamp to the interior of the tube and a bulb upon the exterior of said pipe.

In testimony whereof, I have signed my name to this specification, in the presence of two subscribing witnesses.

GEORGE LEWIS HOGAN.
